BARBER CHAIR OR SIMILAR ARTICLE

George E. Parker, Pasadena, Calif.

Application July 23, 1954, Serial No. 31,571

Term of patent 14 years

(Cl. D15—3)

Fig. 1 is a side elevational view of a barber chair showing my new design;

Fig. 2 is a side perspective view thereof, on a reduced scale, with the back in a lowered position;

Figs. 3 and 4 are front and rear perspective views, respectively, on a reduced scale, of the barber chair.

The dominant features of the design reside in the portions shown in full lines.

I claim:

The ornamental design for a barber chair or similar article, substantially as shown and described.
